JOHN BREWER, OF PHILADELPHIA, PENNSYLVANIA.

Letters Patent No. 79,198, dated June 23, 1868.

IMPROVEMENT IN EXPANDING-MANDREL.

The Schedule referred to in these Letters Patent and making part of the same.

TO ALL WHOM IT MAY CONCERN:

Be it known that I, JOHN BREWER, of the city of Philadelphia, and State of Pennsylvania, have invented a new and improved Adjustable Contraction-Tap; and I do hereby declare that the following is a full, clear, and exact description of the same, reference being had to the accompanying drawing, and to the letters of reference marked thereon.

My invention consists of one or more cutters, arranged around a hollow circular stock, and having such relation to the stock and a cutter-head or holder, that they are contracted or expanded by the raising or lowering of the cutter-head. The tap is especially adapted to the manufacture of gas and steam-fittings, and other connections for wrought-iron pipes.

On reference to the accompanying drawing, forming a part of this specification—

Figure 1 is a view of the tap, with a section of the fitting, showing the cutters and thread.

Figure 2 is a vertical section, with the cutters contracted, to admit of the tap being withdrawn from the fitting without reversing the tap or stopping the machine, and

Figure 3 is an end view of the cutter-head or holder.

Similar letters refer to similar parts in the several views.

A is a hollow cylindrical stock, having one or more spirally-inclined slots, *a*, about midway of its ends, and one or more radial openings, *b*, near its lower end, which extend in the direction of its length. B is a swivel-rod, fitting snugly the stock A; its lower end is, for a short distance, slightly reduced in diameter, to receive the cap C, which is pinned or otherwise secured to it. D is a screw-rod, its upper end being provided with a head, *f*, which takes into the cap C, and is thereby prevented from lifting or rising, while at the same time it is allowed a perfectly free rotation. E is a cylindrical plug, cutter-holder, or head, which takes on the screw-rod D. A jam-nut, *c*, preserves it in its relative position after it has been adjusted. Made longitudinally on the cutter-head E, and at equal distances apart, are several inclined grooves, *d*, any number of which can be used. They receive the inner ends of the adjustable contraction-cutters F F F, the grooves in the cutters taking over the lips *g* of the grooves in the cutter-head, and the ends of the cutters resting firmly on the bottoms of the same; the cutters fitting snugly the radial openings *b* in the stock A.

The distance of the top of the cutter-holder E from the cap C adjusts the gauge of the cutters, which distance is regulated by screwing the cutter-holder up or down on the screw-rod D, after which the swivel-rod B and its accompanying parts are inserted into the stock A until the upper ends of the inclined grooves in the cutter-holder are in a line with the bottom ends of the radial openings *b*, in the stock. The cutters F are then set in the openings *b*; the swivel-rod is moved up the stock until either hole *e* in it adjusts itself to the slots *a*, care being taken to press firmly on the cutters while pushing the swivel up into the stock. A pin or lever, G, is now passed through the slots in the stock and the hole in the pin, projecting both ways from the stock, being locked by taking into the corners or lower ends of the slots *a*. The tap has now the required gauge for tapping fittings, as is shown in fig. 1, where it has gone the required distance into the fitting H. The pin or lever G is now held fast, and the stock A continuing to rotate, it is carried up the slots *a*, the swivel-rod B and its accompanying parts being carried up with it, until it takes into or is locked in the upper ends of the same slots. The cutters F having only a radial movement, and being held in the inclined grooves of the cutter-head, it follows, since the grooves incline outwardly or towards the outer end of the cutter-head, that the cutters must be contracted when the cutter-head rises in the stock, as is shown in fig. 3, so as to be easily withdrawn from the fitting H, without stopping the drill-press or tapping-machine, or reversing the tap; and for the same reason, when the cutter-head descends, the cutters ride or travel up the inclined grooves, and are expanded.

The cutter-head can be adjusted by many other known mechanical devices than by the screw-rod D; therefore I do not confine myself to its use; neither do I confine myself to any method of holding the cutters in the inclined grooves of the cutter-head.

I at first proposed to raise and lower the cutter-head by means of a pin, which projected through horizontal slots in opposite parts of the surface of the stock, into inclined slots formed in a collar on the stock, the collar

being held from raising or lowering by set-screws, which took into a groove formed around the stock, but was at liberty to rotate freely. Handles for turning the collar were fixed oppositely to it.

What I claim as my invention, and desire to secure by Letters Patent, is—

The cutter-head E, in combination with the screw-rod D, cap C, swivel B, slotted stock A, and the rod G, as shown.

In testimony whereof, I hereunto sign my name to this specification in presence of two subscribing witnesses.

JOHN BREWER.
